Primary Examiner — Jae Liang*Assistant Examiner* — Tia Ruth-Renee Polidori**CLAIM**

The ornamental design for a water bottle, as shown and described.

DESCRIPTION

FIG. 1 is a top, rear perspective view of a water bottle showing my new design;

FIG. 2 is a bottom, rear perspective view thereof;

FIG. 3 is a front elevation view thereof;

FIG. 4 is a rear elevation view thereof;

FIG. 5 is a left side elevation view thereof, the right side elevation view being a mirror image of the left side elevation view;

FIG. 6 is an enlarged top plan view thereof;

FIG. 7 is an enlarged bottom plan view thereof; and,

FIG. 8 is a top, front perspective view thereof with the bottle lid being detached.

The broken lines in the drawings illustrate portions of the water bottle that form no part of the claimed design.
